UNITED STATES PATENT OFFICE.

GEORGE DANIEL HAYES, OF HILLSBORO, TEXAS.

ADJUSTABLE WINDOW-SHADE.

1,207,551.

Specification of Letters Patent.

Patented Dec. 5, 1916.

Application filed November 11, 1915. Serial No. 60,915.

To all whom it may concern:

Be it known that I, GEORGE D. HAYES, a citizen of the United States, residing at Hillsboro, in the county of Hill and State 5 of Texas, have invented a new and useful Adjustable Window-Shade, of which the following is a specification.

This invention relates to an improvement in adjustable window shades, and the object 10 is to provide a shade which may be raised and lowered in its entirety, and which may be operated in the usual manner.

A further object is in the provision of a carrier for the window shades which is 15 capable of being expanded and contracted for various lengths of shades.

A further object is in the provision of means which forms a part of the carrier for maintaining the shade against the window 20 casing and prevent it from being blown away therefrom and becoming broken.

The invention will be best understood from a consideration of the following detailed description, taken in connection with 25 the accompanying drawings forming part of this specification, with the further understanding that while the drawings show a practical embodiment of the invention, the latter is not confined to any strict con- 30 formity with the showing of the drawings, but may be changed and modified so long as such changes and modifications come within the scope of the appended claims.

In the accompanying drawings:—Figure 35 1 is a view in front elevation of the invention showing it applied to a window casing. Fig. 2 is an end view. Fig. 3 is an enlarged detail view in top plan of a portion of the shade roller and its bracket. Fig. 4 is an 40 end view. Fig. 5 is a sectional view on the line 5—5 of Fig. 1. Fig. 6 is a detail view in elevation showing another means of sup- porting the carrier.

A represents the window casing, upon 45 which is mounted a longitudinal strip 1 which is fastened thereto by means of screws or nails 2. Brackets 3 are mounted upon the longitudinal strip 1, and the brackets are provided with sockets 4 in which the 50 terminals of the longitudinal strip 1 are received for maintaining the brackets in position. Mounted on the brackets 3 is a spring roller 5.

7 designates a carrier which is preferably 55 constructed from a single length of wire. The intermediate portion of the wire is

arched or looped downwardly, is curved or rounded outwardly and oppositely from the ends of the arch into substantially the same horizontal plane, as at 8, and is curved upwardly as at 10. The opposite ends of the wire are then bent inwardly toward each other in substantially the same horizontal plane, as at 9. The lengths 8 incline slightly backward from the arch 7 to the rounded 60 ends 10 of the carrier, while the lengths 9 lie substantially in the same transverse vertical plane rearwardly of the vertical plane of the arch 7. The lengths 9 are returned forwardly upon themselves to provide forward lengths 11, the joining bends 70 12 being large and rounded.

The forward lengths 11 extend outwardly and oppositely toward the rounded ends 10, but terminate short of the same in downwardly extending loops having inner and outer arms or jaws 13 and 14. These loops comprise brackets to receive the opposite ends of a shade roller 15.

In mounting the shade roller 15, which 80 is of any standard construction, between the terminals of the carrier 7, the brackets are spread apart sufficiently to permit of the insertion of the ends of the shade roller between the vertical jaws 13 and 14. Upon 85 the mounting of the shade roller between the jaws 13 and 14, a wire or cord 16 is connected to the bends 12 for drawing the brackets together to the required extent, and for holding the same from expanding and 90 allowing the shade roller to become disengaged from the carrier. When it is desired to remove the shade roller from the carrier, a terminal of the wire or cord 16 is unwound and disengaged from one of the 95 bends 12, when the brackets of the carrier can be separated and the shade roller removed therefrom.

Ropes or cables 17 are secured at one end to and wound upon the spring roller 5 and 100 have their opposite ends extending downwardly and are connected to the bends 12 of the carrier 7. These ropes or cables support the shade roller at various elevations, and upon the actuation of the carrier 7 the 105 ropes or cables 17 can be caused to wind upon or unwind from the roller 5 for the purpose of raising or lowering the shade and shade roller.

Connected to the roller 15 is a shade 18, 110 which preferably hangs down against the window casing, and in rear of the carrier 7;

that is, the inverted arch-shaped portion and the laterally extending portions 8 of the carrier bear against the shade 18 and hold it against the window casing, so that when 5 the window is open the shade will be prevented from blowing. If desired, the shade can be inserted in front of the carrier and over the laterally extending portions 8 thereof, so that the carrier will be concealed 10 behind the shade.

Connected to the window casing are vertical guides or guide wires 19, the terminals of the guides being connected to the window casing by screws or other means 20. The 15 guides or wires 19 extend between the portions or sections 9 and 11 of the carrier for guiding the carrier in its movement and preventing it from swinging outwardly.

When it is desired to raise or lower the 20 shade roller 15 and the shade 18, the carrier 7 is either pulled down or moved upwardly, causing the ropes or cables 17 to be either wound on or unwound from the roller 5. The shade roller 15 in this manner can be 25 held at any desired elevation.

The carrier 7 is constructed of wire of sufficient resiliency to permit of its expansion and contraction to fit various lengths of shade rollers, and the sections 9 are 30 caused to extend inwardly and toward each other a sufficient distance along the shade rollers so that the ropes or cables 17 which are connected at the inner terminals of the sections 9 will be prevented from traveling 35 over the ends of the roller 5.

While I have shown a carrier 7 supported by the ropes or cables 17, it is possible to dispense with the ropes or cables 17 and 40 fasten the carrier to the window casing by means of nails or hooks 22 passing beneath the sections 9 and 11 of the carrier.

From the foregoing it will be seen that it 45 is possible to raise and lower the shade and shade roller to any elevation for the purpose of admitting light and air to a room through either the upper or lower sash of a window, and the carrier 7 will maintain the shade in engagement with the window casing to prevent 50 the incoming air from blowing and tearing the shade. Furthermore, by mounting the roller 5 upon the top of the window casing the face or outer surface of the casing is not marred in any manner. The only 55 connections which are applied to the outer face of the casing are the guides 19, which are connected thereto by the screws or other fastenings 20.

What is claimed is:—

60 1. A support for window shades comprising a carrier constructed of a single length of wire arched at its intermediate portion,

and provided with bearing brackets at its opposite ends which are adapted to receive and support the ends of a shade roller, the 65 arched portion of said carrier serving to yieldingly hold the brackets in predetermined spaced relation, and means for drawing the free ends of the wire toward each other to hold said brackets over the opposite ends of the shade roller, the arched portion being of a material length and width, so as to depend downwardly below the brackets in front of the shade hanging from 70 said roller and prevent it from being blown and torn.

2. A support for shade rollers comprising a single length of wire arched at its intermediate portion and having lengths extending outwardly and oppositely from the ends 80 of the arch, the ends of the wire being curved upwardly and extended inwardly toward each other and being then curved forwardly and returned upon themselves to provide horizontal bends at the top of the carrier, 85 the returned portions terminating in downwardly extending bracket arms adapted to be sprung over the opposite ends of a shade roller, and securing means joining said bends to hold the brackets from spreading away 90 from the shade roller after their engagement with the latter.

3. A shade support comprising a carrier made from a single piece of material bent at its center to form an inverted arch, the 95 terminals of the carrier extending laterally from the arched portion and then upwardly and inwardly, then bent outwardly from the inner terminals of the inwardly extending portions, and then downwardly at right 100 angles from the outwardly extending portion, so as to form brackets for a shade roller, said arched portion being of a material width and length to depend downwardly 105 below the brackets alongside of the shade hanging from the shade roller, so as to maintain the shade in position.

4. A window shade support comprising a carrier made from a single piece of material bent at its center to form an arched 110 portion, the terminals of said carrier having brackets formed therein for the reception of a shade roller, said arched portion being of a material length and width to depend downwardly 115 below the brackets alongside of the shade hanging from the shade roller, so as to maintain the shade in position.

In testimony, that I claim the foregoing as my own, I have hereunto affixed my signature in the presence of two witnesses.

GEORGE DANIEL HAYES.
